SUPPORTING MEANS FOR HINGED COVERS

George W. Lyons, Jr., West Haven, and John M. Lyons, North Guilford, Conn.

Application June 21, 1950, Serial No. 169,312

4 Claims. (Cl. 16—80)

1

The present invention relates in general to supports for hinged members and more especially to superior supporting means for a hinged cover such as, for example, a hatch cover, bulkhead, box cover, automobile hood, and the like.

An object of the invention is to provide a superior hinged cover supporting means of simple, durable and economical construction.

A further object of the invention is to provide a hinged cover supporting means with superior resilient means for holding the cover in its closed position and for assisting in raising the cover.

A still further object of the invention is to provide superior fastening means for detachably securing resilient means to the supporting means of a hinged cover.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a perspective view, partly broken away, of a bulkhead having a hinged cover embodying the superior supporting means of this invention;

Fig. 2 is an enlarged broken side elevation partly in section of the inner face of the right-hand wall of the bulkhead of Fig. 1 showing a portion of the hinged cover of the bulkhead held in its raised position by the supporting means of this invention;

Fig. 3 is an enlarged broken front elevation of the right-hand wall of the bulkhead of Fig. 1 showing a portion of the corresponding edge of the hinged cover and the supporting means in the relative positions of Fig. 2;

Fig. 4 is an enlarged perspective view of one of the yokes for detachably securing the resilient means to the linkage of the cover supporting means of this invention;

Fig. 5 is similar to Fig. 2 but shows the cover in its closed position on the bulkhead;

Fig. 6 is an enlarged broken front elevation partly in section, of the right-hand wall of the bulkhead and corresponding edge of a portion of the cover, showing a modification of the resilient means of the hinged cover supporting means of this invention, the cover of the bulkhead being shown in its raised position; and

Fig. 7 is an enlarged fragmentary front elevation of details of the detachable fastening means of the resilient means shown in the modified structure of Fig. 6.

2

The showing of Figs. 1 to 5 inclusive

The exemplary embodiment of the invention illustrated in Figs. 1 through 5 is used in conjunction with the hinged cover of a bulkhead comprising a pair of substantially triangular-shaped side panels 11—11, a steel sill bar 12 fastened between the forward ends of the side panels, a head plate 13 fastened across the upper edges of the side panels adjacent the rear ends thereof, and a substantially rectangular cover 14, the side panels, head plate and cover being formed preferably of sheet metal such as, for example, 12-gauge sheet steel.

The cover 14 is hinged at one edge to the head plate 13 of the bulkhead by hinge means such as, for example, bar-iron hinges 15.

Since the bulkhead shown herein is merely for the purpose of illustrating an embodiment of the invention, other structural details of the bulkhead not essential to an understanding of the invention are omitted.

The invention relates in particular to supporting means for the hinged cover 14, two such supporting means being provided, as indicated generally at 16—16, each connected to the inner wall of the respective side panel 11 of the bulkhead and to the underside of the cover 14 adjacent the corresponding edge thereof, and each comprising a linkage embodying a relatively long lever arm 17, a shorter lever arm 18 and coil springs indicated generally at 19 having detachable fastening means hereinafter described for connecting the springs to the arms 17 and 18.

The upper end of arm 17 of each linkage is pivotally secured as at 20 to the cover 14 by means of an L-shaped bracket 21 secured to the underside of the cover adjacent its corresponding edge, as shown in Figs. 1 and 3. The opposite end of each long arm 17 is curved to provide a short crooked portion 22, hereinafter referred to as a "crook," which makes an angle with respect to the longitudinal axis of the arm, the crook 22 being provided at its outer extremity with an aperture for accommodating a stud for the purpose hereinafter described.

Formed integrally with or otherwise secured to each arm 17 in the plane thereof and adjacent the bend of its crook 22, is a pair of spaced lugs forming a bifurcated bracket 23. The latter projects inwardly substantially perpendicular to the longitudinal axis of the lever arm and has axially aligned apertures at the outer extremities of its lugs for accommodating a pivot pin 24 by which the outer end of the shorter

arm 18 is pivotally secured between the lugs of the bracket 23, the pivot pin 24 constituting the fulcrum point of the linkage.

The inner end of each short lever arm 18 is pivotally secured as at 25 to a mounting bracket 26 secured to the inside wall of the corresponding side panel 11 of the bulkhead, each short lever arm 18 being disposed in a vertical plane substantially coincident with the vertical plane of its respective arm 17.

As shown in Figs. 1 and 3, the brackets 21 of the arms 17 are secured to the underside of the cover adjacent the edges of its opposite sides respectively and substantially midway of its front and rear edges, while the brackets 26 of the arms 18 are fastened to the inner walls of the corresponding side panels 11 of the bulkhead adjacent the upper rear end portions thereof. Thus, when the cover is in its normal closed position, as shown in Fig. 5, the arms of each linkage 16 form a V, the short arms 18 extending forwardly and downwardly and the long arms 17 extending rearwardly and downwardly, the fulcrum point 24 of the arms coinciding with the apex of the V. On raising the cover 14 as indicated in Figs. 1 and 2, the short lever arms 18 of the linkages swing upwardly in a counterclockwise direction, carrying the fulcrum points 24 of the linkages upwardly above the upper edges of the bulkhead, while the long lever arms 17 swing outwardly away from the short lever arms, thereby straightening the linkages.

For the purpose of resiliently holding the cover of the bulkhead down in a normal closed position and up in its open position as well as to assist in straightening the pivoted lever arms of each linkage as the cover is raised, there is provided a pair of coil springs 27-27 and a pair of detachable fastening means hereinafter referred to as "yokes" 28-28 by which the springs are connected to the lever arms. These yokes are substantially equilateral triangular plates, each having apertures 29-29 in the oppositely disposed corners of its base for accommodating the respective ends of the pair of coil springs 27-27, and a keyhole-shaped aperture 30 at its apex.

Each yoke of the spring means is adapted to be detachably secured to one of the lever arms of a linkage. Thus, each arm 18 is provided adjacent its inner end with a stud 31 which is secured at its inner end to the arm adjacent the inner pivoted end thereof. The shank of each stud 31 projects inwardly substantially perpendicularly to the inner face of its respective lever arm 18, as shown more particularly in Fig. 3, and is provided at its outer end with a flanged head 32. Mounted on the shank of each stud between its flanged head and the inner face of the respective lever arm is a collar 33, the outer end of which is spaced from the flanged head of the corresponding stud and serves as an abutment for a yoke 28 mounted thereon, the keyhole-shaped aperture 30 of the yoke enabling the latter to be engaged over and detachably secured beneath the flanged head of the corresponding stud.

Similarly, each arm 17, and in particular its apertured crook 22, is provided with a stud 34 projecting inwardly substantially perpendicularly to the inner face thereof, said stud 34 having a flanged head 35 and a collar 36 by which the second yoke of the springs 19 of the corresponding linkage are detachably secured to the inner end of the respective arm 17.

As assembled on the arms 17 and 18 of the respective linkages, the yokes are adapted to support the pair of coil springs 27-27 between the corresponding lever arms, the relationship of the studs of the respective lever arms of each linkage being such that when the lever arms are in a normal position such as shown in Fig. 5, wherein the cover of the bulkhead is closed, the springs 27-27 are under maximum tension, whereas, when the cover is raised to its open position as shown in Figs. 1 and 2, the springs will be under minimum tension, the minimum tension of the springs being sufficient, however, to hold the cover securely in its open position and to hold the narrow portions of the keyhole-shaped apertures 30 of the yokes in cooperative engagement with the flanged heads of the respective studs of the lever arms so as to retain the yokes thereon. It will be clear from the foregoing description of the construction of the resilient means 19 that the magnitude of the force acting on the lever arms of a linkage may be readily varied by using interchangeable yokes adapted to support as few as one or as many as three or more springs, the keyhole-shaped apertures of the yokes permitting the latter to be engaged over and detachably secured beneath the headed studs of the lever arms with facility and dispatch.

Referring to Fig. 5, when the cover of the bulkhead is closed, in which position the arms of each linkage form a V with the studs 31 and 34 of the lever arms are spaced apart a maximum distance with respect to each other and the stud 34 of the long lever arm 17 is below and rearwardly of the fulcrum point 24 of the lever arms. As indicated by the arrow f in Fig. 5 the force vector of the tensioned coil springs 27-27, acts in a line through the two studs 31 and 34, which line of force passes below the fulcrum point 24 of the lever arms, so that the direction of the force is upwardly and rearwardly. As a result, the upper arm 17 of each linkage is urged to pivot in a clockwise direction about its respective fulcrum point 24, each arm 17 thereby exerting through its pivotal connection 20 with the hinged cover a resultant force indicated generally by the vector R, which acts on the cover forwardly of its hinges 15 and in a forward and downward direction, whereby the vertical, downwardly directed component of force tends to hold the cover closed. It will be apparent by a vector analysis that this downward component, while substantial, is still comparatively light so that it may be relatively easily overcome by an upward pull upon the cover.

Now, by exerting sufficient force on the underside of the cover to overcome the aforesaid downward component of the resultant forces R-R imposed on the door by the counterbalance linkages, the hinged cover may be raised up, the lower arms 18-18 swinging upwardly in a counterclockwise direction thereby moving the fulcrum points 24-24 of the levers upwardly through arcs having radii corresponding to the lengths of the short lever arms; and lifting the long lever arms 17-17, the upper pivoted ends 20-20 of which move along arcs having radii substantially equal to the distance from the cover hinges 15-15 to the pivotal connections 20-20 of the long lever arms.

Due to the angular relationship of the lever arms of each linkage and the manner of connecting the springs thereto, the downward component of the two resultant forces R, induced by the springs acting in a direction to hold the cover

closed, will continue to act in this general direction as the cover is opened but will decrease constantly in magnitude until the arms 17 and 18 of each linkage are disposed substantially at right angles to each other, that is to say, when the fulcrum point 24 of each linkage is in a substantially horizontal plane coincident with the pivotal point of the lower arm 18 of the respective linkage, in which condition there is no vertical component produced on the cover by the reaction of the springs through the linkage. Further upward movement of the cover causes the linkage to pass through such dead center condition, after which the two resultant forces R act in an upward and forward direction on the cover, this time producing a vertical, upwardly directed component, thereby assisting in raising the cover.

It will be clear, therefore, that the cover will be resiliently restrained from opening by the springs 27-27 as long as the fulcrum points 24-24 of the linkages are below the pivotal points 25-25 of the short lever arms thereof and that as soon as the fulcrum points are moved above the pivotal points of the short lever arms, the springs 27-27 act to assist in raising the cover. In this connection, it will be clear that as the cover is swung upwardly into its fully raised or open position, the studs of the respective lever arms of each linkage move closer together, thereby reducing the tension of the springs so that the cover is held open by a relatively light force, this force being sufficient, however, to securely hold the cover in its open position.

To close the cover, force must be exerted thereon to swing it downwardly, its downward swinging movement being resisted by the tensioning of the springs 27-27 of each linkage as the respective lever arms thereof collapse. This resistance to closing continues until the lever arms are disposed at substantially right angles to each other, after which further downward movement of the cover is assisted by the force of springs 27-27 acting to pull the cover down and resiliently hold it in its closed position.

The showing of Figs. 6 and 7 inclusive

In the showing of Figs. 6 and 7 inclusive, certain of the parts correspond to those previously described herein and such parts have reference characters applied thereto which correspond to those previously employed.

The modification shown in Figs. 6 and 7 relates in particular to the resilient means of the linkages and is designed to provide greater latitude in the number of springs used with each linkage of the hinged cover. To this end, both the short lever arm and the long lever arm of a linkage are provided with a pair of yokes 28-28, each pair of yokes of the long lever arm 17 being supported on opposite sides respectively thereof and in spaced substantially parallel relationship thereto by means of a single stud 37 which extends through the transverse aperture of the crook 22 of the long lever arm and is provided with a pair of collars 38-38 mounted on the outwardly and oppositely projecting shanks thereof. Flanged heads 39-39 are provided on the outer ends of the stud shanks and serve to hold a pair of keyholed yokes 28-28 thereon in the manner hereinabove described.

Similarly, the short lever arm 18 is provided with a stud 40 which extends therethrough and is adapted to support collars 41-41 thereon on the opposite outwardly projecting shanks there-

of, the opposite ends of the stud shanks having flanged heads 42-42 for holding a pair of keyholed yokes 28-28 thereon.

There are thus two pairs of yokes for the resilient means of each linkage, each pair of yokes being provided in the preferred embodiment with two coil springs 27-27, two of the four coil springs being mounted on one side of the linkage and two of the coil springs being mounted on the opposite side of the linkage, as shown in Fig. 6. As in the previous disclosure, the yokes of the modified structure of Figs. 6 and 7 are adapted to be readily interchangeable with similar yokes for supporting fewer or more than two coil springs so as to vary the magnitude of the resultant force R which acts to hold the cover closed and to assist in raising the cover and holding it open as and in the manner hereinabove described.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

We claim:

1. In an article having a hinged cover, the combination including: supporting means for said cover, said supporting means comprising a linkage fastened to said cover and to said article having headed studs projecting therefrom; resilient means adapted to be connected at its opposite ends to said linkage normally to resiliently hold said cover closed and to assist in raising said cover; and fastening means at the opposite ends of said resilient means, said fastening means comprising yoke members, each yoke member having a keyhole slot arranged to engage over a headed stud of said linkage to detachably connect the yoke member of the corresponding end of said resilient means to said linkage.

2. In an article having a hinged cover, the combination including: supporting means for said cover, said supporting means comprising a linkage fastened to said cover and to said article, said linkage comprising a pair of lever arms, one of said lever arms being fulcrumed intermediate its opposite ends on the free end of the other lever arm of said linkage, the free end of the said one lever arm being bent and provided with a headed stud projecting therefrom, and a headed stud projecting from the said other lever arm of said linkage; resilient means comprising a coil spring adapted to be connected at its opposite ends to said linkage normally to resiliently hold said cover closed and to assist in raising said cover; and fastening means at the opposite ends of said coil spring, said fastening means comprising yoke members, each yoke member having a keyhole slot arranged to engage over a headed stud of the corresponding lever arm of said linkage to detachably connect the yoke member and the corresponding end of said coil spring to said linkage.

3. In an article having a hinged cover, the combination including: supporting means for said cover, said supporting means comprising a pair of lever arms, one of said lever arms being pivotally secured to the underside of said cover and the other of said lever arms being pivotally secured to a wall of said article, the said one

lever arm being fulcrumed intermediate its opposite ends on the free end of the said other pivoted lever arm of said linkage, the free end of said one lever arm being bent and provided with a headed stud projecting therefrom, and a headed stud projecting from the said other lever arm of said linkage; resilient means comprising a pair of coil springs adapted to be connected at its opposite ends to said linkage normally to resiliently hold said cover closed and to assist in raising said cover; and fastening means at the opposite ends of said pair of coil springs, said fastening means comprising yoke members, each yoke member having a keyhole slot arranged to engage over a headed stud of the corresponding lever arm of said linkage to detachably connect the yoke member and the corresponding end of said pair of coil springs to said linkage, the pivotal connections between the lever arms, the cover, and the wall of said article and the attaching points of the resilient means being so arranged that a maximum force is exerted by the resilient means to hold the cover in its closed position and a minimum force is exerted by said resilient means to hold said cover in its open position.

4. In an article having a hinged cover, the combination including: supporting means for said cover, said supporting means comprising a pair of linkages fastened to the opposite edges respectively of said cover and to the corresponding walls of said article, each of said linkages comprising a pair of lever arms, one of said lever

arms being fulcrumed intermediate its opposite ends on the free end of the other lever arm of the corresponding linkage, the free end of the said one lever arm being bent and provided with a headed stud projecting therefrom, and a headed stud projecting from the said other lever arm of said corresponding linkage; a pair of resilient means, each comprising a pair of coil springs adapted to be connected at its opposite ends to corresponding linkages normally to resiliently hold the cover closed and to assist in raising said cover; and fastening means at the opposite ends of each respective pair of coil springs, said fastening means comprising yoke members, each yoke member having a keyhole slot arranged to engage over a headed stud of a lever arm of the corresponding linkage to detachably connect the yoke member and the ends of the corresponding pair of coil springs to the corresponding linkage.
